MEANS FOR DISPOSING OF GARBAGE

Ernest L. Coble and Sallie L. Coble, Cleveland
Heights, Ohio

Application September 1, 1931, Serial No. 560,638

1 Claim. (Cl. 146—123)

This invention has for its object the provision of means whereby garbage may be reduced to a fine pulpy condition and at once discharged into a sewer to be disposed of with other sewage. The 5 invention is illustrated in the accompanying drawings and will be hereinafter fully described and particularly defined.

In the drawings:

Figure 1 is a longitudinal vertical section through an apparatus embodying the invention,

Fig. 2 is a transverse vertical section on the line 2—2 of Fig. 1,

Fig. 3 is a view, partly in plan and partly in horizontal section, on the line 3—3 of Fig. 2,

Fig. 4 is a similar view taken on the line 4—4 of Fig. 1.

In carrying out the present invention, there is provided a base or stand 1 of any convenient or preferred form having a longitudinal housing 2 disposed upon one end portion and provided through its opposite end portion with an opening 3, as shown in Fig. 1. Secured upon the base or support 1 over the opening 3 is a lower casing 4 having its bottom contracted to form an outlet 25 nozzle 5 which depends through the opening 3, as shown clearly in Figs. 1 and 2. The nozzle 5 is constructed with an encircling flange 6 which rests upon and is bolted to a mating flange 7 at the upper end of a trap 8 which communicates 30 with a sewer and is provided with a suitable clean-out plug, as indicated at 9. The casing 4 is provided with flanges 10 through which suitable bolts are inserted to engage in the supporting base and secure the base firmly thereon. As shown most 35 clearly in Fig. 2, the casing 4 has a substantially cylindrical portion intermediate its top and bottom and its top is open to permit the entrance of the garbage which is to be treated. In one side of the casing 4 is fitted a block 11 having stationary blades 12 formed on its inner side and the inner surface of this block is concave and disposed concentric with the rotating grinder shaft 13 which extends axially through the casing and carries a grinding or breaking block or cylinder 40 14 upon which are arranged series of breaker or cutter blades 15 which are arranged in spiral relation so that, as the cutter or breaker rotates, the blades 15 will successively cooperate with the stationary blades 12 to pulverize and break up the 45 50 55 garbage. The shaft 13 extends through journal boxes 16 provided therefor upon the ends of the casing and is coupled to the driving shaft of a motor 17 which is supported upon the base 1 with in the housing 2 and may be of any approved form, being illustrated conventionally. Preferably, a

flexible coupling 18, which is shown conventionally, is utilized to couple the shaft 13 with the motor. Immediately above the blade-carrying block 11, the wall of the casing is turned inwardly, as shown at 19, to form a breaker or guard 60 which will prevent material being drawn too rapidly by the rotor and will arrest the downward travel of large hard pieces of garbage and will thereby overcome the liability of the blades 15 to be broken by sudden impact upon such objects 65 as, for instance, bones or pieces of broken crockery or silverware. These objects will be retained within the casing until they have been worn down to such an extent that they may pass between the cooperating blades without damage thereto. 70

At the upper edge of the casing 4, upon the sides of the same, are flanges 20 upon which rest, and to which are secured, flanges 21 at the lower end of a hopper 22. This hopper is of an elongated inverted bell form, as shown most clearly in Fig. 2, and rises to an appreciable height above the casing 4 so that it gives ample room for the deposit of garbage and the holding of the same while the lower portion is being pulverized. In the top of the hopper is an opening 23 through 80 which any convenient form of pusher may be inserted so as to positively force the accumulated matter onto the grinding or breaking roller or cylinder and insure the maceration of the same. This opening 23 is normally covered by a cap 24 85 which may be pivotally or hingedly mounted in place in order that it may be easily moved from over the opening without being lost whenever the occasion arises. The hopper is provided with a vertically extending horizontally contracted inlet opening 25 in one side and from said opening an inlet conduit or branch hopper 26 rises, as shown in the drawings, this branch hopper or conduit being provided with a circular upper end intended to register with an opening 27 in 95 a table 28 which is arranged immediately adjacent the hopper and is provided with a retaining flange around its entire edge, as shown. The garbage is to be dumped upon this table and the attendant will be provided with some suitable implement whereby it may be spread and pushed into and through the opening 27 and any tableware or matter which should not pass to the sewer or the macerating elements, which may have been gathered with the garbage, may be 100 detected and reclaimed. Preferably, the table will be connected with the branch hopper 26 at one end by a hinge 29 and will be supported by a prop 30 at its opposite end whereby it may be 105 swung upwardly when not in use and thereby 110

facilitate cleaning of the hopper and be out of the way.

A hollow rim or annular chamber 31 is formed around the upper end of the branch hopper 26 and in the bottom of this annular chamber are perforations 32 which are located immediately adjacent the inner surface of the wall of the branch hopper so that water fed into the annular chamber may flow down through the hopper 10 and wash the garbage into and through the apparatus and the sewer. The water is admitted to the annular chamber through a supply pipe 33 connected with the house water system and having a branch 34 leading directly into the annular chamber. A second branch 35 extends downwardly alongside the branch hopper and has its terminal secured in and passing through the block 11 so as to discharge in the lower portion of the casing 4. It will be noted upon reference to Fig. 2 that the terminal of the branch pipe 35 is disposed approximately tangential to the grinding roll 14 and consequently the stream issuing therefrom will pass to the outlet nozzle 5 and play directly upon the pulverized matter 25 which has been fed thereto by the grinding or breaking roller. The branches 34 and 35 are connected with the supply pipe 33 through a T-coupling 36 and in the supply pipe, in advance of said coupling, is a valve 37 which may be of 30 any well known type and is illustrated in a conventional manner only. Preferably, the valve will be a gate which is pivoted at one side of the valve casing and is adapted to move across the bore of the supply pipe. The pivot of the 35 valve is extended through one side of the valve casing and has a lever 38 secured thereon, said lever having a fork 39 at its outer end which receives a switch handle 40 controlling a switch mounted within a switch casing 41 which is carried by a bracket 42 secured upon the water pipe. It will thus be seen that when the lever 38 is 40 rocked to open or close the valve 37, one side of the fork 39 will impinge against and actuate the switch handle 40 so that the switch will be 45 shifted to close or break the circuit controlling the motor 17. The motor will thus be permitted to run only when garbage is being treated and water is flowing into the hopper. It is to be understood, of course, that the machine need 50 not be driven by a motor but may be actuated by hand and for this purpose, the shaft 13 is provided at one end with a tenon 43 adapted to be engaged by any convenient turning tool.

The wall of the hopper 22, immediately above 55 the inlet opening 25 and at its junction with the branch 26, is flared outwardly, as shown at 44, and at the lower end of the inlet opening 25 is formed an inwardly projecting lip 45.

In use, the garbage is fed through the opening 60 27 to the branch hopper 26 and will pass through the narrow vertically elongated inlet opening 25 into the hopper 22 wherein it will fall onto the grinding or pulverizing roller 14. This roller is rotated so that the abrupt ends of the blades 15 will be opposed to the abrupt ends of the blades 12 in action and, consequently, garbage which may be engaged between the blades will be very effectively broken up and reduced to a pulpy condition, the flow of water accelerating the reducing of the garbage and also aiding in feeding the same through the apparatus. The blades 15 will 65 just clear the breaker guard or lip 19 and, consequently, there will be no jamming of the parts due to any matter being caught between the

breaker and the blades, but any such matter, such as bones, will be caused to roll toward one end of the casing due to the spiral arrangement of the blades 15 and the consequent successive presentation of the same to the breaker. As a result of this action, bones and similar articles will be gradually chipped or broken without damaging any of the working parts of the machine. The roller 14 rotates at some speed and light matter, such as shreds of lettuce or small vegetables, tends to rise or flow back from the grinder within the hopper. Experience has demonstrated that these lighter elements tend to work back to and out of the mouth of the hopper, but, in the present apparatus, this objection is overcome by the provision of the deflecting lip 45 and the flared surface 44 and by the design of the hopper. The lighter particles which may be thrown upward by the action of the grinder or breaking roll will be deflected from the inlet opening 25 by the lip 45 and if such elements should be thrown up to the top of the hopper, the flared wall 44 will deflect them over the inlet opening so that they will be returned immediately to the pulverizing chamber, it being noted that the lower edge of the flared wall 44 and the upper end of the inlet opening 25 are somewhat below the top of the hopper and the branch hopper is flared above the lower edge of the wall 44 so that there is a restricted passage in the plane of the lower edge 100 of said wall and, consequently, the objectionable backflow will be effectually arrested. The hopper is of such shape that the garbage and flushing water will be retained therein while being ground or macerated, notwithstanding that the bore of 110 the rim 31 remains open. While the material may be thrown around and up against the top of the hopper by the rapidly moving rotor, it will always fall back onto the rotor and will eventually pass through the device and into the sewer. After 115 all the garbage has passed, the flow of water and the movement of the rotor are continued for a short period during which the hopper will be washed by the clear water being thrown against its inner surface.

From the foregoing description, taken in connection with the accompanying drawings, it will be seen that we have provided an exceedingly simple and compact apparatus by the use of which garbage will be very effectually pulverized 125 and reduced to such form that it may be readily carried off through the house sewer connections. The block 11 carrying the stationary blades 12 is removable and it is therefore possible to replace broken or worn out blades 12 without requiring 130 the provision of an entirely new casing. The removability of the block 11 also facilitates inspection and cleaning of the lower casing.

Having thus described the invention, we claim:

Apparatus for the purpose set forth comprising 135 a casing, a pulverizing roll within the casing, stationary blades on the wall of the casing cooperating with the pulverizing roll, a hopper rising from the casing and having an inlet opening in one side, a branch hopper rising from the side of the 140 hopper around the inlet opening, a table hingedly connected to the upper end of the branch hopper and having an opening therethrough registering with the branch hopper, and means for supplying running water to the branch hopper and to the 145 casing.
